UNITED STATES PATENT OFFICE.

WILLIAM L. MCKEAN, OF MARTINS FERRY, OHIO, ASSIGNOR TO STEEL WORKS APPLIANCE COMPANY, OF PITTSBURGH, PENNSYLVANIA, A CORPORATION OF PENNSYLVANIA.

TIN-PLATE-CLEANING MACHINE.

1,414,365.

Specification of Letters Patent. Patented May 2, 1922.

Application filed August 28, 1917, Serial No. 188,625. Renewed September 24, 1921. Serial No. 502,997.

To all whom it may concern:

Be it known that I, WILLIAM L. MCKEAN, residing at Martins Ferry, in the county of Belmont and State of Ohio, a citizen of the 5 United States, have invented or discovered certain new and useful Improvement in Tin-Plate-Cleaning Machines, of which improvement the following is a specification.

In the operation of a tin plate cleaning 10 machine, the plates or sheets are transferred from the tinning machine to the feed rollers of the cleaning machine by suitable means such as endless belts, and not infrequently the plates or sheets will so drop onto the 15 endless belt that a sheet or plate will overlap to a greater or less extent a preceding sheet, and the sheets be fed into the cleaning machine in such overlapping positions, and hence portions of both sheets will not be subjected to the action of the cleaning rolls.

The invention described herein has for its object the provision of means whereby the movement of the one of two overlapping sheets is arrested until the other sheet has 25 been moved entirely away from the rear sheet. The invention is hereinafter more fully described and claimed.

In the accompanying drawing, forming a part of this specification, Fig. 1 is a sectional 30 elevation of the front portion of a cleaning machine including the feed rollers, a conveyor whereby the sheets are carried to the latter and the improvement claimed herein; Fig. 2 is a top plan view of the same.

35 In the practice of the invention, the cleaning machine is constructed in the usual or any suitable manner and in front thereof are arranged feed rollers as is customary, said rollers consisting of a plurality of spaced 40 discs 2 secured upon driven shafts 3. These feed rollers are arranged in such relation to the machine as to feed the sheets into the bite of the first pair of cleaning rollers 4. In front of the feed rollers is arranged a suitable 45 transferring mechanism such as an endless belt 5 passing around suitable pulleys 6, one or both of which may be driven to carry the sheets deposited upon the belt, forward into the bite of the feed rollers. As these 50 sheets drop onto the belt from the tinning machine, the front edge of one sheet may, and frequently does, lap onto or extend under the rear edge of the preceding sheet and both sheets are carried forward in such 55 position into the feed rollers and by them passed into the cleaning machine. By rea-

son of this overlapping relation, portions of the sheets are not subjected to the action of the cleaning machine.

In order to insure the movement of all the 60 sheets or plates into the cleaning machine, each entirely clear of any preceding or following sheet, provision is made for engaging the forward edge of a sheet which laps onto or extends under the rear edge of a preceding 65 sheet and to hold such following sheet stationary until the overlapping relation has been changed. Convenient means for effecting this separation of the sheets consists in radial fingers 7 having their inner ends 70 secured to collars 8 mounted upon the shafts 3 intermediate of the spaced discs 2 forming the feed rollers. These collars are so mounted as to be frictionally driven by the shafts so that when the outer end of the 75 finger rests upon a sheet the shaft can rotate independent of the collar. These fingers are so formed that their outer ends will project beyond the peripheries of the feed rollers, as clearly shown in Fig. 1.

In the operation of the machine, the collars with their fingers are carried around by frictional engagement with the shafts until the ends of the fingers rest upon the sheet passing into the bite of the feed rollers, 85 whereupon the movement of the fingers and collars is arrested until the rear edge of such sheet has passed beyond the fingers when the latter will be carried around by frictional engagement with the shafts. 90 Each of the collars is provided with a plurality of fingers so as to insure a finger being brought to bear against the upper or under side of a sheet as it is carried into the bite of the rolls by the belt. If the rear portion 95 of the sheet in the bite of the rollers is overlapped by or overlaps another sheet, the fingers bearing lightly on such sheet will engage the forward edge of the rear sheet and hold it as against movement until after the preceding sheet has passed beyond the finger, whereupon the finger will be carried out of the way of the following sheet which can then be moved forward into the bite of the rollers.

105 While it is usual for the front end of a succeeding sheet to lap onto the rear end of a preceding sheet, the reverse occurs occasionally and hence it is preferred to arrange these arresting fingers on the shafts 110 of both the upper and the lower feed rollers as shown.

The frictional engagement of the shafts with the collars carrying the fingers causes the latter to yieldingly bear on the sheets and will insure the prompt movement of

5 the collars and fingers as soon as a sheet has passed beyond the ends of the fingers toward the cleaning machine.

I claim herein as my invention:

1. The combination of a tin plate cleaning 10 machine with means for feeding the plates to said machine and means adapted to engage the front end of a sheet overlapping another without interrupting the forward movement of the sheet nearer the cleaning 15 machine and to move out of engagement with the rear sheet.

2. The combination of a tin plate cleaning 20 machine with means for feeding the plates to said machine and means for preventing the rearmost of two overlapping sheets from moving between the rolls of the cleaning machine until the front sheet has passed out of overlapping relation with the rear sheet.

3. The combination of a tin plate cleaning 25 machine with means for feeding plates to said machine, movable fingers and means for applying a yielding pressure to said fingers to move them across and out of the path of movement of sheets being fed to the cleaning 30 machine.

4. The combination of feed rollers of a tin plate cleaning machine, means for feeding plates to said rollers and frictionally operated fingers adapted to bear on the plates 35 as they are moved into the bite of the rollers.

5. The combination of a tin plate cleaning 40 machine with means for feeding the plates to the machine and means operative in conjunction with the feeding means on overlapping plates to cause one of such plates to be shifted out of such overlapping relation to the other.

6. The combination of feed rollers consisting of a plurality of spaced discs, collars 45 arranged on the shafts of said rollers intermediate of the discs, and frictionally driven,

fingers extending radially from collars beyond the peripheries of the discs, and means for feeding plates into the bite of said rollers.

50

7. In a sheet separating means, the combination of lower and upper feed wheels opposed to each other, lower and upper loosely rotatable disks opposed to each other, and blades carried by one of said disks and extending beyond the perimeter thereof.

8. Sheet separating means for use in conjunction with sheet feeding means, comprising lower and upper disks one of which is provided with blades that extend beyond its 60 perimeter.

9. In a conveyor for sheets, means for preventing the feeding of sheets in superposed relation, said means comprising a constantly rotated shaft overlying the path of travel 65 of said sheets, a hub frictionally carried by and rotatable on said shaft, and fingers carried by said hub, said fingers being so disposed that one thereof rides upon the top surface of an advancing sheet and obstructs 70 the advance of a second sheet in superposed relation to the first-mentioned sheet.

10. In a conveyor for sheets, means for preventing the feeding of sheets in superposed relation, said means comprising a 75 member rotatably mounted over the path of travel of said sheets and out of engagement with sheets traveling in said path, a plurality of spaced radial fingers carried by said member, said fingers being so disposed that one 80 thereof rides upon the top surface of an advancing sheet in a position presenting its end in arresting relation to a second sheet having its front end in closely overlapping relation to the first-mentioned sheet, and that 85 the next succeeding finger automatically assumes like riding relation to such second sheet when the first-mentioned sheet has passed out of reach of said fingers.

In testimony whereof, I have hereunto set 90 my hand.

WILLIAM L. McKEAN.
